Daniel Harrington (146) 9455X

The Schedule refers to an item of Daniel Harrington and making proof of the same containing a description of the walls of the house of the said Daniel Harrington himself of his improvement in the said proof safety vault for keeping of Books papers &c.

It all whom it may concern. Be it known that I Daniel Harrington of the City of Philadelphia in the State of Pennsylvania have invented a safety vault case & other apparatus connected with the same which I do nominate for proof apparatus for the safe keeping of Books, papers, Chamber and other things during the combustion of buildings.

The performance of the vault is to be laid of brick, stone or other material and brought up even with the bottom of the cellar. Then the walls of the vault of the stone or material will be to be composed of two thicknesses, from one to four feet, that may be dressed nearey, and continual supports will be even with the top of the first floor above, or a double wall may be caused up leaving an air dimension of 2.4. or 6 inches between the inner and outer wall. Which the walls may be brought up one over the top, leaving an outlet for the escape of noxious air at their junctions. Between the side and outlet for noxious air at their bottom which outlet may be expressed also through the inside wall, that outlet for air may be by means of a tube from the out side of the building or from the bottom of the cellar. The dimensions of the vault will be commencing at the bottom, may be one and a half feet three feet which size may be continued to within three feet from the top, at which height a shoulder of six inches is to be made on all sides for sloping. Solved in these widths the inner surface of the walls are nine inches for the purpose of stringing may be by under 2 or 3 inches below the outlet and for the purpose of forming a chamber at present may be laid 2.4. or 6 inches above the walls.

may then be carried up leaving the minimensions of that part of the vault two feet by 3 to 4 without one part of that top, at which part is taught another off set similar to the above described, either north or without division and may be made and the walls continued to that top, at which case the division is to be placed as described above, but need not be made more than one inch or two inches above the top, at this sum is made by the guides the top case being left to be associated to its place and also prevent water from running into the vault. The other case need not be made larger by it is to stop first middle and bottom from dissolving stones and then it is to be either of stone by having a small notch in the brick work passing slightly downwards to the bottom of the cellar and side of the wall and to the an bottom in case of a double wall. Between the brick wall of the vault & the cellar wall, according to the first middle and bottom notch may be made of desirable a small box case from bottom to top of any necessary dimensions in which a concrete weight box after to be mounted from top up and down, the case for containing books, papers or other articles may be made of wood or metal of ^{and} iron and wood that will permit it to open long ways the front part of the vault and it may have a small notch attached to its side to prevent it from crossing with the cellar wall, the cellar is then letting down and removing up, at the bottom of the vault case is to be closed and can be by a hook or eye or some kind of spring force or mechanical attachment (or these may also be done if these can be attached secure to the wall by tenons and edges weighing light) this box will be of one inch wide by 15 4 inches wide and of sufficient length when the top part is a little above or below the bottom case open to the top of the case below, the offset first middle and bottom of the upper end of this box may be two holes, one before the other, one hole to receive the edge or other end which is to open

seen a couple of pulley blocks, which are to be attached to the joists of the floor of the second story of the building, the other end of a long iron chain is to be attached to the center of the upper block. The latter is to be lowered (but not quite) as heavy as the case and apparatus and suspended by it, and the apparatus will necessary consist of two thick iron bars (of wrought or cast iron) one to project loosely above and just before the lowest edge of the case (and the other to rest upon the second offset beam). Note that, across the beam of a mortise in the center of each through which the iron bar is to be inserted, will be drawn up and let down with the case, one by one, lifting upon the bar, will always adjust themselves to their places, that they in the middle or above it, a small shoulder may be left before the bar above its attachment to the case, or a portion of the front through it which would end in the middle of the bar, so as to may slide quite down upon the bar and rest upon the top of the case. The second hole from the top of the bar may have a pin or key through it which may be of iron, wood, bone or whatever it is, which pin will, or may be made to rest across the mortise in the middle corner and sustain the weight of the case below & its contents. The top most beam to be made of wrought iron cast iron (and of very necessary thickness,) and made hollow at each of its ends very 1 to 1½ inches so as to sustain the two ends of the case at the top and project over each of the front the case at center of 10 inches. This case may run upon four small wheels which are to be made without them. From the center of this case to one of the side edges should be a groove or opening wide enough to admit the front of the chain when the case is drawn in the wall, thereby permit this case to be run over the surface of the wall as the last resort to the house, and then may be run over to work by means

of one or two fuses to burn over and close this groove & exclude fire from passing through it. If this last course should be well fastened down by each hand of iron it will constitute a safety bank against thieves as well as against fire. Then the case will be as in the top course it is to be removed from over the mouth of the barrel and the case, and its apparatus being a trifle heavier than the counterweight in slight elevation of strength will be sufficient to hold up it above the top course. So then the case is to be now brought to its place & the case is offered to stand on end opposite the mouth of barrel, it is now at right will be fastened by the mode of letting it down at right will be fastened by this fire proof apparatus as above described. This survivor fastened to be sufficient for the purpose of excluding additional safety this case may be exploded or fire below the bottom of the barrel as may be desired in this part of it made of planks, beams and girders, or of other materials above or below the bottom of the barrel a trap or falling door may be set with hinges or other means to close part of the barrel with appropriate offsets to stand or fall upon and which door similar to last closing part of the trifle to stand the survivor so that at will fall of itself and close the barrel when it is. Should be provided upon partition way to close large slender posts of wood so that the weight of the case should be readily thrown out of its way and thereby close door after itself in case it should be made to jump before its usual depth upon any occasion. This partition enclosure is sufficient when the case is above. In all cases where this additional depth of barrel is constructed this is to hang on the second side of the barrel in its uppermost part above described similar to of some material that will ignite as soon as wood be off from any circumstance when should become so mortified as to prevent fire to pass downward and cast up in the 2^d tier by drawing away the step or

spring-sprgs (a chain in this case should not be used) the case and box will instantly fall to the bottom (and close the trap door after it) and a small spring which should be made to this purpose on upper side of the lower case cover will close the mouth by sliding over it. & thereby prevent ~~any~~ ^{the} case from falling through, the same kind of spring may be attached to the middle cover if deemed necessary. Off the middle of the box covers by projecting forward, when the case is up, should be in the way, about $\frac{1}{3}$ of their front edges may be made to turn up, by means of springs & most against the box, during the day, is turned down or back, where about to let the case down, there are other ways to provide this apparatus may be raised (and lowered) such as the wheel, & tackle, but by more difficulty, perhaps as by the one above described. Both the vault and case may be raised as to their dimensions, according to desire, while other wise principles are retained. As a combination of old and new forces or principles forming an invention this inventor believes himself to be entitled to it. To the trap door most mode of shooting by the case itself to the particular construction of the vault well or chamber to the particular construction of the top cover (which should be turned down at the edge opposite to the groove the case is at this side) to the mode of raising the lower cover so as to slide upon the box & be placed & replaced conveniently with the hoisting (and lowering) of the case. Convenience-facility or saving of time & labour in the bending, and the particular manner of suspending the case so that the element of fire itself by concreting the fire and case causes the case to become below its former distance, although in this going description I have mentioned the various parts which I believe to be peculiar with myself, I do not intend to claim this invention.
